United States Patent

Des. 234,328
Patented Feb. 11, 1975

234,328

HOMOGENIZER

Douglas S. Fraser, New Paltz, and Robert P. Adams,
Walden, N.Y., assignors to Cenco Medical/Health
Supply Corporation, Chicago, Ill.

Filed Nov. 17, 1972, Ser. No. 307,410

Term of patent 14 years

Int. Cl. D15—08

U.S. Cl. D98—1 A

FIG. 1 is a perspective view of a homogenizer showing our new design;

FIG. 2 is a top plan view of the homogenizer shown in FIG. 1; and

FIG. 3 is a right side view of the homogenizer shown in FIG. 1.

We claim:

The ornamental design for a homogenizer, as shown.
